STEP TABLE

Forest Wilson, Chicago, Ill.

Application March 13, 1956, Serial No. 40,586

Term of patent 3½ years

(Cl. D33—14)

FIG.1

FIG.4

Fig. 1 is a perspective view of the step table embodying my new design;

Figs. 2 and 3 are end and side elevational views, respectively, of the step table; and

Fig. 4 is a top plan view thereof.

I claim:

The ornamental design for a step table, substantially as shown.
